(57) **CLAIM**

The ornamental design for a wireless HDMI transmitter, as shown and described.

DESCRIPTION

FIG. 1 is a perspective view of a wireless HDMI transmitter; FIG. 2 is a front view of the wireless HDMI transmitter; FIG. 3 is a back view of the wireless HDMI transmitter; FIG. 4 is a first side view of the wireless HDMI transmitter; FIG. 5 is a second side view of the wireless HDMI transmitter;

FIG. 6 is a top view of the wireless HDMI transmitter; and, FIG. 7 is a bottom view of the wireless HDMI transmitter. The broken lines immediately adjacent the shaded areas represent the bounds of the claimed design while all other broken lines are directed to environment and are for illustrative purposes only; the broken lines form no part of the claimed design.
